UNITED STATES PATENT OFFICE.

JOHN T. McGARRY, OF CINCINNATI, OHIO.

WATER COLUMN.

Application filed August 18, 1919. Serial No. 318,429.

To all whom it may concern:

Be it known that I, JOHN T. McGARRY, a citizen of the United States, and a resident of Cincinnati, in the county of Hamilton and State of Ohio, have invented certain new and useful Improvements in Water Columns, of which the following is a specification.

My invention relates to railway water-
10 columns and more especially to those which swing parallel with the track when not in use and are swung around across the track to discharge into the locomotive tanks and which usually have a loose connection be-
15 tween the delivery spout and a projecting curved spout extending from the head of the stand-pipe. Such water-columns by the loose connection of the spout, afford considerable adjustment to tanks of different
20 heights; but have several disadvantages involved in the operation of swinging them into and out of discharging position as will hereinafter be more fully alluded to.

The object of my invention is to facilitate
25 this bringing of the water-column into dis-
charging position conveniently and at the same time have it efficient in operation by minimizing the height to which the water
30 must flow in the column and thereby utiliz-
ing an ample proportion of the total avail-
able "head" in the water supply system in
which the column is installed.

My invention consists in the combination
35 of parts and in the details of construction
and arrangement of parts as will herein-
after be more fully described and claimed.

In the drawings:

Fig. 1 is a plan view of a water-column embodying my invention, swung into dis-
40 charging position and also being shown in its inoperative position and in an inter-
mediate position by dotted lines, and parts
of a locomotive tank and adjoining car be-
ing also indicated by dotted lines to illus-
45 trate how the apparatus clears the car when
being swung around;

Fig. 2 is a side elevation of the water-
column of Fig. 1 with its spout at an inter-
mediate discharging height and also show-
50 ing, by dotted lines, the spout adjusted to
two other discharging heights and the spout
and associated parts also being shown in
their highest or inoperative position by
55 dotted lines, as is also an adjacent part of
the car to further illustrate how the spout

clears the side of the car in being swung around; it being understood that this view of the raised spout and other parts and of the car is at right angles to a plane cor-
responding to the line 2—2 of Fig. 1;

Fig. 3 is a vertical cross-section on a plane corresponding to the line 3—3 of Fig. 2 looking forwardly or to the right of the drawing;

Fig. 4 is an enlarged side elevation of the upper part of the water-column, the spout being shown by full lines in raised position and by dotted lines in lowered position;

Fig. 5 is a side elevation of the upper part of a water-column embodying a modifi-
cation of my invention;

Fig. 6 is a vertical cross-section on a plane corresponding to the line 6—6 of Fig. 5;

Fig. 7 is a view similar to Fig. 4, show-
ing another modification of my invention;
and

Fig. 8 is a rear elevation of the same.

The water-column chosen for exemplify-
ing my invention is of well known construc-
80 tion in its lower parts; comprising the base
1 fixed on the platform 2 and having the
stand-pipe 3 running down through it be-
low the platform to connect to suitable
valve mechanism and having the collar 4
85 that bears on a series of rollers 5 arranged
around on top of the base 1. There is also
a detent disk 6 surrounding the top of the
base 1 having recesses in which engages
the lower end of the detent rod 7 which
90 drops therein by action of gravity and
which has a weight 8 to increase this effect.
These are under a cover 9 that surrounds
the top of the base 1.

The top of the stand-pipe 3 comprises the
95 gooseneck 10 which curves over and slightly
downward to one side and has a beveled end
to discharge in a somewhat downwardly in-
clined direction. On the top of this gooseneck
10 where it curves over from the main part 100
of the stand-pipe 3 is a standard 11 on the
top of which is bolted a head 12 that pro-
jects forward over the gooseneck 10 and
there has upwardly projected laterally
spaced lugs 13 between which a beam 14
105 has its web 15 fixed by transverse bolts 16.
This beam projects forward and upward a
considerable distance past the end of the
gooseneck 10, where it has fixed on its bot-
tom flanges 17 a downwardly projected fork 110

18, the members 19 of which are adapted to straddle the top of the delivery spout 20.

This delivery spout tapers somewhat from its open rear end to its somewhat downwardly curved open front end and its rear end surrounds the gooseneck 10 very loosely, being of considerably greater cross-section than the gooseneck.

As shown in Figs. 1 to 3, inclusive, a 10 slotted guide 21 extends along the top of the gooseneck and follows the curvature thereof, and a divided bracket 22 has its members straddling this guide 21 with a pin 23 transversely through these members and through 15 the guide slot. This bracket 22 is fixed to the top of the rear end of the delivery spout 20 by extending thereover and being riveted thereto.

Sheaves 24 are journaled on the top of the 20 beam 14 at opposite sides above the fork 18, and cables 25 are connected to the top of the spout 20 near its curved front end and run back over these sheaves 24 and over sheaves 26 journaled on opposite sides 25 of the standard 11, and then these cables 25 pass down along the opposite sides of the stand-pipe 3 and are connected to a weight 27 that loosely surrounds the stand-pipe with a recess at its rear for the passage 30 of the detent rod 7. A bracket 28 provides the journal bearings for the sheaves 24, being bolted to the upper flanges 17' of the beam 14.

The detent rod 7 extends up to the top of 35 the column through a guide lug 7' on the back of the lower part of the standard 11, and the upper end of this rod 7 is pivoted between the rear end parts of two handles 29 which, from these parts, curve around 40 opposite sides of the standard 11 and have fulcrums 30 in a yoke 31 that projects out at opposite sides from the front part of the head 12. These handles 29 extend forward and terminate in loops 32. Vertical 45 guide straps 33 on the sides of the standard 11 receive the rear parts of the respective handles 29 and reinforce the fulcrums 30 in the connection of these handles to the rest of the apparatus.

At the front end of the beam 14 is a 50 fulcrum bracket 34 in which is pivoted a bell crank having the forwardly extended arm 35, and having the upwardly extended arm 36 pivoted to the front end part of a connecting rod 37 which has its rear end part pivoted to one arm 38 of another bell crank. The head 12 has, just to the rear of its lugs 13, a bearing 39 for this bell crank which has its rearwardly extended 55 arm 40 provided with a slot 41 by which it is suitably connected to a rod 42 that extends down through the column for connection to the valve mechanism under the platform 2. Such valve mechanism being 60 of various kinds and well known, need not

be disclosed herein; it being sufficient to say that an upward pull on the rod 42 opens the valve and permits the water to flow up through the stand-pipe 3 and out through the gooseneck 10 into the delivery 70 spout 20.

In the modification of Figs. 5 and 6 the yoke 21' is fixed on the bottom of the front end part of the head 12 straddling the delivery spout 20' and having at opposite sides of this spout the slotted guides 21'' through which the spout 20' has trunnions 23' projecting up near its top at opposite sides. This yoke and these trunnions thus serve a purpose similar to that of the slotted 80 guide 21 and bracket 22 with its pin 23 in the preceding example and the other details are like the corresponding ones in that example.

In the modification of Figs. 7 and 8 there 85 is a bracket 22' fixed on the top of the spout over the gooseneck 10, and arms 43 flank the rear end part of this spout, bending in over the top thereof, and are pivoted to this bracket 22' and, extending downward, are bent in toward each other and are both pivoted to a swivel bolt 44 turning sidewise in a lug 45 on the front side of the stand-pipe 3. This construction also operates in substantially the same way as 90 the preceding examples and the other details are like the corresponding ones in those examples.

When not in use, the stand-pipe 3 and delivery spout 20 and supporting parts therefor are swung around to the side of the track as indicated by the dotted lines at A in Fig. 1. The locomotive tank 46 is stopped with the water hole 47 opposite the stand-pipe, and the attendant, standing on the top of the tank, engages a hook in the adjacent handle loop 32 pulling down on the handle 29 and raising the detent rod 7 out of the detent disk 6 and then pulling the apparatus around until the delivery 110 spout extends out across the tank. The delivery spout, owing to its raised position as at B in Figs. 1 and 2, clears the adjacent corner 48 of the car next to the tank. Then the attendant pulls the spout 20 down by grasping it in any convenient place. The spout preferably has laterally projecting 115 handles 49 near its front end, for this purpose. This pulls the weight 27 up by the cables 25 running over the sheaves 24 and 26, and brings the delivery spout down within reach of the attendant's hand by which it is pushed down into the water hole 47; the delivery spout being now moved down whatever distance is required to bring it 120 into the water hole 47 of the tank 46 of any given height. The lowest dotted lines at C in Fig. 2 indicate such an adjustment to a very low tank. The full lines indicate 125 such an adjustment to a higher tank. If 130

the tank is very high the position of the spout is indicated by the higher dotted lines at D in Fig. 2.

The water is then let into the tank by 5 opening the water-column valve by means of the bell-crank arm 35 and a chain 50 attached thereto; the delivery spout being held down as usual by the foot of the attendant.

10 When sufficient water has been admitted to the tank the valve is closed by pulling the chain 51 attached to the other arm 36 of the bell crank, and the spout is allowed to swing up under the action of the weight 27. The 15 parts are then pushed around along side the track as before. The lower ends of the chains 50 and 51 are preferably connected to the top of the spout 20, so as to prevent their entanglement. If the valve is self- 20 closing, the chain 51 may be omitted.

When the parts swing around to the side of the track the detent rod 7 again engages in the detent disk 6 and locks the apparatus in this position as is well known in the art. 25 Other means for insuring that the apparatus will not be inadvertently swung across the track are well known in the art and it will be understood that this detent mechanism is only illustrative of such means in general. 30 Likewise with the valve operating mechanism, of which there is a variety well known, and of which the details shown herein are merely illustrative.

The important advantages of this invention are that without bringing the gooseneck 10 or other highest outlet means any higher than is necessary merely to afford a proper incline therefrom to the water hole of the highest tank, the delivery spout is given a 35 position for swinging it around without striking the adjacent corner of the highest car which may be next to the tank. Where no provision is made for raising the delivery spout as herein it is necessary to have the gooseneck 10 or other highest water-outlet 40 means higher than the highest car that may be encountered; or else if such a height is not provided and the water-column is approached in the direction indicated in Fig. 45 1 so that the car projects past the delivery spout end, the apparatus can not be swung around. In such cases it is necessary to carefully stop the train back far enough to permit this swinging around and then carefully bring the train forward with the tank 50 water hole opposite the stand-pipe. And it frequently happens several backward and forward movements of the train are necessary to do this, owing to the difficulty to 55 stop the train at any exact point. Such an operation as this requires the careful attention of two or more of the train operatives as well as the other usual expenses of moving the train and amounts to a considerable 60 loss of time.

If the water-column is made high enough to avoid these difficulties, as just before alluded to, a considerable proportion of the "head" of water is lost; because this effective "head" is only that measured from 70 the upper level of the water in the water tank or other source of supply to the water-column, and the gooseneck 10 or other highest outlet means in the water column. The 75 higher this outlet means the less will be the effective "head."

By providing a combination of parts that permits of ready raising and lowering of the spout together with the swinging around it is unnecessary to sacrifice this "head" 80 and there will be no difficulty in swinging the apparatus around and no necessity of carefully adjusting the train as just before described.

In any of the examples where the delivery 85 spout is hung on its pivot for swinging up and down this pivot is permitted a considerable motion in a transverse plane so that the delivery spout may be swung slightly sidewise in either direction to admit 90 it to the tank water hole even though the train has not been adjusted to an exact position. This also avoids breakage of the parts by slight movement of the train in one direction or the other while the spout is in the 95 water hole. Such slight movement or creeping of the train nearly always occurs and is practically unavoidable. In the examples of Figs. 1 to 4, this lateral swinging of the 100 spout is permitted by having the members of the bracket 22 spaced amply from the sides of the slotted guide 21 so that the pin 23 may swing around in this slot. Likewise with the members of the yoke 21' at the opposite sides of the slots 20' in Figs. 5 and 105 6. In Figs. 7 and 8 this is permitted by virtue of the swiveled bolt 44 that supports the arms 43 on which the spout 20'' is hung.

In any of the examples of my invention this novel upward swinging of the delivery 110 spout is provided for without sacrificing any of the adjustability thereof to locomotive tanks of different heights. With the slotted guides of either Figs. 1 to 4 or Figs. 5 or 6 the delivery spout may move bodily 115 across the track in either direction as is required to bring its discharge end into the water hole at the middle of the tank of any given height; and with the arms of Figs. 7 and 8 this same adjustment across the 120 track is provided for. And in any of the examples the novel upward swinging is accompanied by a swinging of the rear end of the delivery spout back to its rearmost position—with the pivot 23 against the rear 125 end of the slot of the guide 21 or the trunnions 23' against the rear ends of the slot of the guide 21'', and in Figs. 7 and 8, with the top of the rear end of the delivery spout 130 20'' down against the top of the gooseneck

10 next to the standard 11. This automatic rearward adjustment of the delivery spout along with the upward swinging affords the maximum clearance from the car as the 5 parts are swung around.

While certain constructional details are deemed preferable in connection with my invention, and I have shown and described these rather specifically in elucidating the 10 construction and use of my invention, as is required, I do not wish to be understood as being limited to such precise showing and description, but having thus fully described my invention, what I claim as new and de- 15 sire to secure by Letters Patent is:

1. In a water-column, a delivery spout, discharging means, supporting means for said spout whereby it is swung across or away from a track, upwardly inclined sup- 20 porting means for said spout whereby it is swung into a position for delivering from said discharging means or into a position materially inclined upward from said discharging means, for clearance of rolling 25 stock on the track when said spout is swung across or away from said track, discharge-controlling means, operating means on said upwardly inclined supporting means, a connection between said operating means and 30 said discharge-controlling means and means for revolving said spout transversely, substantially as set forth and for the purposes specified.

2. In a water-column, a delivery spout, 35 discharging means, supporting means for said spout whereby it is swung across or away from a track, and a loosely connected supporting means for said spout whereby it is swung into a position for delivering from said discharging means or into a position materially inclined upward from said discharging means, for clearance of rolling 40 stock on the track when said spout is swung across or away from said track, or whereby 45 said spout may swing laterally with and relative to the stand pipe, substantially as set forth and for the purposes specified.

3. In a water-column, a stand-pipe comprising a gooseneck and a standard above 50 said gooseneck, a head on the top of said standard, a beam mounted on said head over said gooseneck, a delivery spout receiving said gooseneck loosely, an articulated connection between said spout and said stand- 55 pipe near said gooseneck, a loose connection between said spout and said beam, supporting means for said stand-pipe permitting it

to swing transversely, detent means to prevent said standpipe swinging transversely, handles flanking said standard and connected to said detent means, and laterally extended pivots for said handles on said standard. 60

4. In a water-column, a stand-pipe comprising a gooseneck and a standard above 65 said gooseneck, a head on the top of said standard, a beam mounted on said head over said gooseneck, a delivery spout receiving said gooseneck loosely, an articulated connection between said spout and said stand-pipe near said gooseneck, a fork depending 70 from said beam with members flanking said spout, a sheave on said beam above said fork, a sheave on said standard, a cable connected to said spout and passing 75 over said sheaves, a counter-weight hung on said cable along said stand-pipe, supporting means for said stand-pipe permitting it to swing transversely, detent means to prevent said stand-pipe swinging transversely, handles flanking said standard and connected to 80 said detent means, and laterally extended pivots for said handles on said standard. 85

5. In a water-column, a stand-pipe comprising a gooseneck and a standard above 90 said gooseneck, a head on the top of said standard, a beam mounted on said head over said gooseneck, a delivery spout receiving said gooseneck loosely, an articulated connection between said spout and said stand-pipe near said gooseneck, a fork depending 95 from said beam with members flanking said spout, a sheave on said beam above said fork, a sheave on said standard, a cable connected to said spout and passing over said sheaves, a counter-weight hung on said cable along said stand-pipe, valve-operating means on said stand-pipe, a bell-crank fulcrumed on said head with an arm connected to said valve-operating means, a connecting 100 rod, another arm of said bell-crank being connected to said rod, a lever on said beam connected to said connecting rod, supporting means for said stand-pipe permitting it to swing transversely, detent means to prevent 105 said stand-pipe swinging transversely, handles flanking said standard and connected to said detent means, and laterally extended pivots for said handles on said standard. 100
